2,570,383

SAFETY CONTROL MEANS FOR TIMBER
SETTING MACHINESJohn D. Russell, Franklin, Pa., assignor to Joy
Manufacturing Company, Pittsburgh, Pa., a
corporation of Pennsylvania

Application June 18, 1948, Serial No. 33,890

10 Claims. (Cl. 121—38)

1

This invention relates to timber setting machines and more particularly to an improved safety control apparatus for the adjustable timber support of such a machine for reducing the possibility of accidental operation of the support adjusting means.

In a timber setting machine of the type disclosed in a copending application to Charles F. Ball and Richard T. Hair, Serial No. 746,646, filed May 8, 1947, owned by the same assignee as the present invention, a portable body is mounted on rubber tired wheels adapted to travel over the floor of a mine or tunnel and carries a pivoted boom frame which, at its outer end, supports a saddle for receiving a mine timber. The boom frame is raised by hydraulic pressure, and hydraulic jack devices are operatively connected to the boom frame for swinging the latter upwardly about its pivot to bring a mine timber on the saddle up against the roof of the mine or tunnel and to hold the mine timber in place during setting of the uprights or props. In accordance with the present invention, in order to reduce the possibility of accidental lowering of the boom frame during setting of the timber, an improved safety control apparatus is provided for trapping the liquid in the cylinders of the jack devices and embodying improved manually operable control valve means for controlling lock release and liquid flow with respect to the jack cylinders when it is desired to raise or lower the boom frame and saddle.

An object of the present invention is to provide an improved timber setting machine. Another object is to provide an improved timber setting machine having safety control apparatus for reducing the possibility of accidental raising or lowering of the adjustable timber support. Yet another object is to provide an improved safety holding apparatus for an adjustable timber support of a timber setting machine wherein improved locking means is associated with the power device for raising the timber support whereby the latter is firmly locked in position during setting of a mine timber. A further object is to provide an improved timber setting machine having a hydraulic cylinder for raising the timber support and an improved safety holding apparatus associated with the cylinder for trapping the liquid therein during setting of a mine timber. Yet another object is to provide an improved control valve means for the lifting cylinder for the adjustable timber support, including a manually operable valve for effecting trapping of liquid in the cylinder and a second manually operable valve for controlling liquid flow with re-

2

spect to the cylinder. Both control valves must be operated prior to lowering of the timber support. A still further object is to provide an improved safety holding apparatus embodying a fluid actuated valve for controlling fluid flow relative to the lifting cylinder for the timber support and separate valves respectively controlling operation of said fluid actuated valve and for controlling fluid flow relative to the cylinder. In the event of failure of the fluid supply, the fluid actuated valve automatically assumes a position wherein it traps the fluid in the cylinder, thereby to prevent accidental lowering of the timber support. Still another object is to provide an improved fluid operated lock for preventing accidental dropping of the timber support, either as the result of accidental movement of the control valve or failure of the pressure fluid in the fluid system. The improved safety device reduces the possibility of accidental raising of the timber support as well as inadvertent lowering of the support. These and other objects and advantages of the invention will, however, herein-after more fully appear.

In the accompanying drawings there is shown for purposes of illustration one form which the invention may assume in practice.

In these drawings:

Fig. 1 is a fragmentary view in longitudinal vertical section, with parts shown in full, through a timber setting machine in which an illustrative form of the improved safety control apparatus is embodied, with the timber support shown in partially raised position.

Fig. 2 is a side elevational view, on a somewhat reduced scale, of the timber setting machine, with the timber support shown in lowered position.

Fig. 3 is a horizontal sectional view, with parts shown in plan, of the improved control valve mechanism.

Fig. 4 is an enlarged detail sectional view taken on line 4—4 of Fig. 2, illustrating one of the hydraulic cylinders.

Fig. 5 is an enlarged view in longitudinal vertical section taken substantially on line 5—5 of Fig. 4.

Fig. 6 is a cross-sectional view taken on line 6—6 of Fig. 5.

Fig. 7 is an enlarged fragmentary sectional view taken through the fluid actuated control valve or valve lock, which is associated with each cylinder.

Fig. 8 is a diagrammatic view illustrating the hydraulic system.

The timber setting machine, as fully disclosed in the application Serial No. 746,646, above referred to, comprises a portable body mounted

on wheels adapted to travel over the floor of a mine or tunnel. The rear wheels 2 are traction wheels and are suitably motor driven, and the front wheels 3 are steering wheels and are swiveled to turn horizontally and are provided with suitable steering gear operated by a hand wheel 4. Extending centrally lengthwise of the machine body is a load carrying compartment 5 and straddling this compartment is an adjustable load support or boom frame 6 carrying, at its outer end, a horizontal turntable or rotatable saddle 7 providing a timber support. Hydraulic jack devices 8 beneath the timber carrying compartment are provided for swinging the boom frame. The load carrying compartment is adapted to receive a load of mine timbering elements, such as cross timbers and props, and when the boom frame and turntable are properly positioned with respect to the timbering element compartment, a timber may be moved lengthwise from the compartment onto the turntable. The boom frame may then be swung upwardly by the jack devices to elevate the turntable above the top of the machine body, and then the turntable may be turned to locate the timber in a crosswise position. The boom frame may then be swung upwardly by the jack devices further to elevate the turntable to bring the cross timber up against the roof and to hold it there firmly during setting of the uprights or props or during insertion of the rib pins.

The hydraulic jack devices 8 each comprise a cylinder 9 pivoted at 10 beneath the compartment bottom, and a plunger 11, reciprocable in the cylinder, is pivotally connected at 12 to a bell crank 13. Each bell crank is pivoted at 14 within the machine body, and is pivotally connected at its opposite end at 15 to a link 16, the latter in turn pivotally connected at 17 to the boom frame 6. Thus, when liquid under pressure is supplied to the cylinders 9 of the jack devices, the plungers 11 are moved outwardly to swing the boom frame 6 upwardly about its pivot through the bell cranks 13 and links 16. When the liquid is trapped within the cylinders, the boom frame is locked in adjusted position and the boom frame may be lowered simply by discharging the liquid from the cylinders.

Now referring to the improved safety control apparatus, it will be noted that arranged at one side of the machine body is a control valve mechanism, generally designated 20, comprising a valve box composed of a series of valve block sections 21 and end head sections 22 and 23 suitably secured in assembled relation. Connected to an inlet chamber 24 in the end head section 22 is a pipe 25 which leads to the discharge side of a conventional pump 26 driven by a motor 27. A discharge chamber 28 in the end head section 23 is connected by a discharge pipe 29 to a liquid tank or reservoir 30. The suction side of the pump 26 is connected by a pipe 31 with the liquid tank. Extending longitudinally through the valve block sections is a passage 32 which connects the inlet chamber 24 with the discharge chamber 28. Arranged parallel with the passage 32 and likewise extending through the valve block sections is a discharge passage 33 communicating with the discharge chamber 28. A conventional spring-loaded relief valve 34 is adapted to connect the inlet chamber 24 with the discharge passage 33 in the event of overload in the hydraulic system. Formed in the left hand valve block section is a bore 35 containing a reciprocable slide valve 36, while contained in a bore 37 in the right hand

valve block section is a similar slide valve 38. An annular groove 39, formed in the walls of the valve receiving bore 35, is connected by a pipe 40 and branch pipes 41 to passages 42 in head blocks 43, suitably secured to rear cylinder heads 44. Each passage 42 communicates with an annular groove 45 formed in the walls of a transverse bore 46 in the head block 43 (see Fig. 7). Also formed in the walls of the bore 46 is an annular groove 47 connected by a passage 48 in the rear cylinder head with the rear end of the cylinder bore 49 at the rear side of the piston head 50 of the plunger 11. An annular groove 51, formed in the wall of the valve receiving bore 37, is connected, by a pipe 52 and branch pipes 53, with the left hand ends of the bores 46, as viewed in Figs. 6 and 7. Reciprocable in each bore 46 is a fluid actuated valve 54 to be later described.

Again referring to the slide valves 36 and 38, it will be noted that these valves are preferably of the balanced spool type, and respectively have suitable operating levers 36' and 38'. The valve 36 has spaced spools separated by reduced portions or grooves 55 and 56 so that when the valve is held in the position shown in Fig. 3 by a coil spring 57, fluid is free to flow from the inlet chamber 24 to the supply passage 32, with the central spool cutting off the groove 39 from both the supply passage and the exhaust passage. When the valve 36 is moved downwardly, as viewed in Fig. 3, the groove 39 may be connected by the reduced portion 56 with the exhaust passage, and when the valve 36 is moved upwardly, the reduced portion 55 may connect the groove 39 with the supply passage 32. The valve 38 has its spools separated by reduced portions or grooves 58 and 59, and when the valve is held downwardly, as viewed in Fig. 3, by a coil spring 60, fluid is free to flow through the supply passage 32 while the groove 51 is connected by the reduced portion 59 with the discharge passage 33. When the valve 38 is moved upwardly, as viewed in Fig. 3, the groove 51 is cut off from the discharge passage and is connected through the reduced portion 58 with the supply passage 32.

Now referring to the detail structure of the spring 57, it will be noted that the slide valve 36 has a reduced stem 61 formed with an annular end flange engaging an inner flange on a sleeve member 62. The spring 57 is arranged between a flange 63 on this sleeve member and a washer 64. When the valve 36 is in the position shown in Fig. 3, the washer 64 is held by the spring against the adjacent end surface of the valve block section, with the sleeve member 62 held against the inner end wall of a cap 65. When the valve 36 is moved downwardly, as viewed in Fig. 3, the sleeve member 62 is moved inwardly, compressing the spring to bring the groove 56 into a position to connect the groove 39 to the exhaust passage 33, thereby to connect the jack cylinders to exhaust. When the valve 36 is moved upwardly from the position shown in Fig. 3, the washer 64 is lifted from its seat, compressing the spring, cutting off communication of the groove 39 with the exhaust, and connecting the groove 39 with the supply passage 32 through the groove 55. The spring 60 acts between the inner end wall of a cap 67 and a sleeve member 68 secured to the valve 38. In Fig. 3, the sleeve member 68 is held by the spring against the adjacent end surface of the valve block section. When it is desired to interrupt communication of the groove 51 with the exhaust passage 33, the valve 38 is raised upwardly, as viewed in Fig. 3. Upon fur-

ther upward movement, the groove 51 is connected by the groove 58 with the supply passage 32. Thus, when the valve 38 is in the position shown in Fig. 3, the groove 51 is connected to exhaust, and when the valve 38 is moved upwardly from the position shown in Fig. 3, the groove 51 is connected to the fluid supply. When the valve 36 is moved upwardly from the position shown in Fig. 3, the groove 39 is connected to the fluid supply, and when the valve 36 is moved into its opposite position, the groove 39 is connected to exhaust.

The fluid actuated valve 54 is preferably of the spool type and has an annular groove 70. The valve is urged toward the left, as viewed in Fig. 7, by a spring 71, arranged between the valve and a threaded plug 72. This plug has an axial vent passage 73 for venting the bore 46 at the right hand end of the valve. Sealing rings 74, arranged in grooves surrounding the valve receiving bore, sealingly engage the end body portions of the valve to prevent leakage. When the valve 54 is in the position shown in Figs. 6 and 7, the groove 45 is cut off from the groove 47, and the valve body, at that time, traps the liquid within the jack cylinder so that when the boom frame is in raised position with the timber held up against the roof, it is firmly held there. When it is desired to lower the boom frame, the operator may actuate the valve 38 to connect the groove 51 with the supply passage 32 so that liquid under pressure may then flow through the pipe 52 and branch pipes 53 to the valve-receiving bores 46 at the left hand ends of the valves 54, moving the latter toward the right from the position shown in Figs. 6 and 7 into a position wherein the groove 70 connects the groove 45 with the groove 47. Liquid may then flow from the cylinders through passages 48 and 42 and through pipes 41, 40, groove 39, and when the valve 36 is in lowered position, through the reduced portion 56 to the discharge passage 33, thereby causing the boom frame to swing downwardly.

When it is desired to swing the boom frame upwardly, the valve 36 may be positioned to connect the groove 39 with the supply passage 32 so that liquid under pressure may flow through pipes 40 and 41, passage 42, grooves 45 and 47 and passages 48 to the cylinders, thereby to move the plungers 11 outwardly.

In the event of failure of pressure in the hydraulic system, as for example, as a result of bursting of the pipe 52, the pressure in the bore 46 at the left hand end of the valve 54 is suddenly reduced, causing the spring 71 to move the valve 54 into its left hand position shown in Figs. 6 and 7, cutting off the grooves 47 from the grooves 45 and trapping the liquid within the cylinders.

While the improved safety control apparatus is shown associated with a timber setting machine of the pivoted boom frame type, it will be evident that the same may be associated with other types of timber setting machines, as, for example, that disclosed in a copending application to L. G. Felderman and A. S. Knoizen, Serial No. 746,832, filed May 8, 1947.

As a result of this invention, an improved safety control apparatus is provided wherein a pair of slide valves must be manually operated in relatively opposite directions to effect venting of liquid from the lifting jacks for the boom frame. By the provision of the fluid actuated valves controlled by one of the hand valves, the liquid is automatically trapped in the lifting cyl-

inders in the event of a failure of pump pressure. By the provision of the independently operable hand valves located at a point remote from the timber support, it is possible for the operator to effect raising and lowering of the timber support while assuming a relatively safe position remote from the timber support. By the provision of the separate hand valves, which are operated in relatively opposite directions, the operator has to operate both of these valves in order to lower the boom frame—one valve to release the pressure from the cylinder and the other to apply pressure to the control valve which permits escape of fluid from the cylinder. The two hand operated valves are so arranged that the possibility of the same being operated either carelessly or inadvertently, thereby accidentally to lower the boom, is substantially reduced. Other uses and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In combination, an adjustable load support, means for elevating said support including a fluid cylinder, a source of fluid under pressure, means providing a passage communicating with said cylinder for supplying fluid to the latter to effect elevation of said support, a manually operable valve for controlling fluid flow through said passage, a normally closed, fluid actuated valve for controlling fluid flow through said passage, means providing a passage for supplying fluid under pressure from said source to said fluid actuated valve for moving the latter into its open position, and a manually operable valve for controlling fluid flow through said last mentioned passage.
2. In combination, an adjustable load support, means for elevating said support including a fluid cylinder, a source of fluid under pressure, means providing a passage communicating with said cylinder for supplying fluid to the latter to effect elevation of said support, a manually operable valve for controlling fluid flow through said passage, a normally closed, fluid actuated valve for controlling fluid flow through said passage, means providing a passage for supplying fluid under pressure from said source to said fluid actuated valve for moving the latter into its open position, and a manually operable valve for controlling fluid flow through said last mentioned passage, said manually operable valves located in mutual adjacency at points remote from said movable load support.
3. In combination, an adjustable load support, means for elevating said support including a fluid cylinder, a source of fluid under pressure, means providing a passage communicating with said cylinder for supplying fluid to the latter to effect elevation of said support, a manually operable valve for controlling fluid flow through said passage, a normally closed, fluid actuated valve for controlling fluid flow through said passage, means providing a passage for supplying fluid under pressure from said source to said fluid actuated valve for moving the latter into its open position, a manually operable valve for

controlling fluid flow through said last mentioned passage, said manually operable valves located in mutual adjacency at points remote from said movable load support, and said manually operable valves movable one in one direction and the other in the opposite direction, toward positions to effect lowering of said support.

4. In combination, a movable load support, means for elevating said support including a fluid cylinder, a source of fluid under pressure, a fluid exhaust, means providing a passage communicating with said cylinder, a manually operable valve for controlling fluid flow through said passage and positionable to connect said cylinder either to said supply source or to said exhaust, a normally closed, fluid actuated valve for controlling fluid flow in said passage to said cylinder, a spring for moving said fluid actuated valve into its closed position, means providing a passage for supplying fluid from said source to said fluid actuated valve for moving the latter into its open position against the action of said spring, and a manually operable valve for controlling fluid flow through said last mentioned passage and positionable to connect said last mentioned passage either to said supply source or to said exhaust.

5. In combination, a movable load support, means for elevating said support including a fluid operated elevating device, a source of fluid under pressure, a fluid exhaust, means providing a passage communicating with said device, an operator controllable valve device for controlling fluid flow through said passage and positionable to connect said passage either to said supply source or to said exhaust, a normally closed, fluid actuated valve means for controlling fluid flow in said passage communicating with said elevating device, means providing a passage for supplying fluid from said fluid source to said fluid actuated valve means for moving the latter into its open position, resilient means acting on said valve means for moving the latter into its closed position when said second mentioned passage is connected to exhaust, and an operator controllable valve device for controlling fluid flow through said last mentioned passage and positionable to connect the same either to said supply source or to said exhaust.

6. In combination, a movable load support, means for elevating said support including a fluid operated elevating device, a source of fluid under pressure, a fluid exhaust, means providing a passage communicating with said device, an operator controllable valve device for controlling fluid flow through said passage and positionable to connect said passage either to said supply source or to said exhaust, a normally closed, fluid actuated valve means for controlling fluid flow in said passage communicating with said elevating device, means providing a passage for supplying fluid from said fluid source to said fluid actuated valve means for moving the latter into its open position, resilient means acting on said valve means for moving the latter into its closed position when said second mentioned passage is connected to exhaust, and an operator controllable valve device for controlling fluid flow through said last mentioned passage and positionable to connect the same either to said supply source or to said exhaust, said operator controllable valve devices located in mutual adjacency at points remote from said load support and one positionable to connect said first mentioned passage to said exhaust and the other to connect said second

75 mentioned passage to said supply source prior to lowering of said load support.

7. In combination, a movable load support, means for elevating said support including a fluid operated elevating device, a source of fluid under pressure, a fluid exhaust, means providing a passage communicating with said device, an operator controllable valve device for controlling fluid flow through said passage and positionable to connect said passage either to said supply source or to said exhaust, a normally closed, fluid actuated valve means for controlling fluid flow in said passage to said elevating device, means providing a passage for supplying fluid from said fluid source to said fluid actuated valve means for moving the latter into its open position, resilient means acting on said valve means for moving the latter into its closed position when said second mentioned passage is connected to exhaust, an operator controllable valve device for controlling fluid flow through said last mentioned passage and positionable to connect the same either to said supply source or to said exhaust, said operator controllable valve devices positionable one to connect said first mentioned passage to said exhaust and the other to connect said second mentioned passage to said supply source prior to lowering of said load support, and said operator controllable valve devices located in mutual adjacency at points remote from said load support and one movable in one direction and the other in the opposite direction, toward aforesaid positions to effect lowering of said support.

8. In combination, a movable load support, means for elevating said support including a fluid cylinder, a source of fluid under pressure, a fluid exhaust, means providing a passage communicating with said cylinder, a manually operable valve for controlling fluid flow through said passage and positionable to connect said cylinder either to said supply source or to said exhaust, a normally closed fluid actuated valve for controlling fluid flow in said passage to said cylinder, a spring for moving said fluid actuated valve into its closed position, means providing a passage for supplying fluid from said source to said fluid actuated valve for moving the latter into its open position against the action of said spring, and a manually operable valve for controlling fluid flow through said last mentioned passage and positionable to connect said last mentioned passage either to said supply source or to said exhaust, and said spring automatically moving said fluid actuated valve to closed position to prevent escape of fluid from said elevating cylinder to prevent inadvertent lowering of said load support in the event the fluid supply fails for any reason.

9. In combination, a movable load support, means for elevating said support including a fluid operated elevating device, a source of fluid under pressure, a fluid exhaust, means providing a passage communicating with said device, an operator controllable valve device for controlling fluid flow through said passage and positionable to connect said passage either to said supply source or to said exhaust, a normally closed fluid actuated valve means for controlling fluid flow in said passage to said elevating device, means providing a passage for supplying fluid from said fluid source to said fluid actuated valve means for moving the latter into its open position, resilient means acting on said valve means for moving the latter into its closed position when said second mentioned passage is connected to exhaust, an operator controllable valve device for

controlling fluid flow through said last mentioned passage and positionable to connect the same either to said supply source or to said exhaust, said operator controllable valve devices located in mutual adjacency at points remote from said load support and one positionable to connect said first mentioned passage to said exhaust and the other to connect said second mentioned passage to said supply source prior to lowering of said load support, and said resilient means automatically moving said fluid actuated valve means to closed position to prevent escape of fluid from said fluid operated device to prevent inadvertent lowering of said load support in the event the fluid supply fails for any reason.

10. In combination, an adjustable load support, means for controlling the elevation of said support including a hydraulic mechanism having a cylinder variably filled with fluid dependent upon the elevation of said support, means for supplying fluid to and for venting fluid from said cylinder comprising a passage communicating with said cylinder for venting fluid from the latter, an operator controllable valve for controlling fluid flow through said vent passage, a normally closed, fluid actuated valve arranged within the outline of said hydraulic mechanism for controlling fluid flow through said vent passage, a source of fluid under pressure, means providing

5 a passage for supplying fluid under pressure from said source to said fluid actuated valve for moving the latter into its open position, and an operator controllable valve for controlling fluid flow through said last mentioned passage, said operator controllable valves each having an individual operating element, said operating elements located in mutual adjacency at points remote from said support and separately movable at the will of the operator one in one direction and the other in a different direction to effect movement of said operator controllable valves into their positions to effect fluid venting from said cylinder.

15
